UNITED STATES PATENT OFFICE.

STANLEY P. LOVELL AND KENNETH D. HAMILTON, OF BROCKTON, MASSACHUSETTS.

DISPENSING CONTAINER.

Application filed January 5, 1923. Serial No. 610,893.

To all whom it may concern:

Be it known that we, STANLEY P. LOVELL and KENNETH D. HAMILTON, citizens of the United States, residing at Brockton, in the county of Plymouth and State of Massachusetts, have invented certain new and useful Improvements in Dispensing Containers; and we do hereby declare the following to be a full, clear, and exact description of the invention, such as will enable others skilled in the art to which it appertains to make and use the same.

The present invention relates to dispensing containers and is more particularly concerned with containers of this type used for solutions or liquids which, upon standing, tend to assume a non-uniform constituency, as, for example, by a settling of undissolved or suspended materials or a stratification of liquid components. When such liquids are being used or dispensed from a container it is necessary to stir or agitate them at frequent intervals in order that the proper composition of the liquids may be secured and the desired results accomplished. Many of these containers are provided with special dispensing means for delivering the liquid in a convenient manner and in the desired amounts according to the character of the liquids and its mode of use.

It is one of the objects of the present invention to provide a dispensing container of the above type with conveniently arranged and efficiently operating means for stirring or agitating the liquid contained therein when the dispensing device is actuated.

Another object of the present invention is to provide a container of the above type with actuating mechanism for the agitating means so connected with the dispensing device that the actuating of the latter automatically effects the actuation of the agitating means.

With these objects in view the present invention consists in the devices and combinations of devices hereinafter described and more particularly defined in the claims.

In the accompanying drawings the present invention is shown as embodied in a dispensing container especially designed and adapted for use in shoe factories for liquid finishing materials. Such containers usually consist of a pan to hold the liquid, a cover for the same, and a dispensing roller projecting above the cover and dipping into the liquid. The operator ordinarily uses

a small sponge to apply the blacking or stain, and he moistens this with the stain by drawing it across the exposed face of the roller, thereby rotating the latter in the liquid. This movement, however, of the roller is not sufficient to keep the liquid properly agitated particularly where pigments are employed which are held rather in suspension in the liquid than in solution, and unless the operator stirs or agitates the liquid at frequent intervals, an objectionable variation in color or shade of shoes treated will result, particularly between those treated at the beginning and at the end of the day.

In the illustrated embodiment of the present invention such a dispensing container is provided with an agitating device in the form of a perforated plate suspended horizontally in the liquid and raised and lowered by the rotation of the roller when the operator draws his sponge across the same to replenish his supply.

In the accompanying drawings Figure 1 is a top plan view of such a container with a portion of the cover broken away; Fig. 2 is a vertical sectional view on line 2-2 of Fig. 1; Fig. 3 is a vertical sectional view taken on line 3-3 of Fig. 1; and Fig. 4 is a detailed longitudinal, vertical, sectional view of the agitating device.

Referring to the drawings, the circular receptacle or pan 6 for the liquid 8 is provided with a dished cover 10 having an annular lip 12 received over the edge of the pan. The cover also has a central rectangular opening 14 to accommodate a moistening roller 16 which is provided with a shaft 18 journaled for rotation in depending ears 20 on the cover. The edges of the opening 14 adjacent the roller are turned inwardly as indicated at 22 to present a finished appearance and so that there may be no sharp edges that could possibly catch the sponge or the operator's hand. The means for agitating the liquid comprises the circular plate 24 having at opposite sides the upstanding ears 26 with circular openings 27 having in-turned flanges 28 to provide bearing surfaces for the actuating cams 29. These cams may obviously be of any desired shape but preferably consist of eccentrics mounted upon the roller shaft 18 adjacent the roller, as shown in Figs. 2 and 3.

The agitator plate 24 is preferably provided with a plurality of apertures or perforations through which the liquid flows

during the raising and lowering movements of the plate. Preferably these are in the form of rectangular openings 30, and in order to insure still further the thorough circulation and mixing of the liquid, the metal from these openings is not wholly removed but is bent upwardly to form inclined vanes or flanges 32 for directing toward the roller the liquid passing up through the openings 30. The agitator plate 24 is also preferably provided with a rectangular slot 36 between the ears 26 to receive the roller 16 when the agitator is in raised position. It will be seen that both the cover and the agitating device may be constructed from single sheets of metal by stamping operations.

In operation the workman draws his sponge across the top of the roller 16, thereby replenishing the supply in the sponge and by rotation of the roller replenishing the supply on the roller. Usually the sponge is drawn across the roller two or three times to ensure an ample supply of liquid in the sponge, any excess being removed by squeezing or pressing the sponge against the sloping surface of the cover 10, the surplus liquid returning to the pan. Upon each revolution of the roller the agitator plate 24 rises and falls through the liquid, at the same time having a back and forth endwise motion due to the action of the cams within the circular openings 27 of the ears 26 of the agitator plate. With this construction, thorough agitation of the liquid and resulting uniformity in the color of the finished product is insured, without any additional mental effort or appreciable physical effort on the part of the operator.

Although in the drawings an agitator plate has been illustrated which is operated through the action of a pair of similarly disposed cams or eccentrics, it is to be understood that other and various forms of agitators may be employed which may be operated by a wide variety of mechanisms without departing from the spirit of the present invention.

Having thus described the present invention, what is claimed is:

50. 1. A dispensing container for liquid comprising a receptacle for the liquid, a closure for the top of the receptacle, means for dispensing the liquid contained in the receptacle, an agitating device for agitating the liquid, and mechanism located within the receptacle and beneath the closure for actuating the agitating device.

55. 2. A dispensing container for liquids comprising a receptacle for liquid, means actuated by the operator for dispensing the liquid container therein, an agitating device

for agitating the liquid, and connections between the dispensing means and the agitating device for actuating the agitating device by the dispensing means, the connections being located within the receptacle. 65

3. A dispensing container comprising a receptacle for the liquid, a depressed slotted cover for the receptacle, a moistening roller mounted within the receptacle and partially submerged in the liquid and projecting through the slotted cover, and means actuated by the rotation of the roller for agitating the liquid. 70

4. A dispensing container comprising a receptacle for the liquid, a dispensing device comprising a moistening roller partially submerged in the liquid, an agitator plate for agitating the liquid, connections for actuating the agitator plate from the roller, 80 and a closure for the top of the receptacle having an opening for the projection therethrough of the roller, the roller and agitating plate being supported on the cover. 85

5. A dispensing container comprising a receptacle for the liquid, a moistening roller, a cam mounted at each end of the roller, and an agitating device submerged in the liquid and suspended upon the cams, whereby the agitating device will be raised and lowered 90 when the roller is rotated.

6. A dispensing container comprising a receptacle for the liquid, dispensing means, an agitating device comprising a plate submerged in the liquid and provided with a plurality of perforations and deflecting vanes, and mechanism for raising and lowering the agitating device in the liquid. 95

7. A dispensing device comprising a pan for the liquid, a cover having an opening 100 therein, a moistening roller rotatably supported on the cover and having its upper portion projecting through the opening in the cover and its lower portion submerged in the liquid, cams at each end of the roller 105 and rotating therewith, and a perforated plate submerged in the liquid having an opening to receive the roller and provided with upstanding ears having openings to receive the cams. 110

8. A dispensing container comprising a receptacle for the liquid, a closure for the top of the receptacle, said closure being provided with an opening, a moistening roller and agitating device connected therewith 115 located within the receptacle and beneath the closure, the top of the roller projecting through the opening in the closure and the bottom of the roller being submerged in the liquid.

STANLEY P. LOVELL.
KENNETH D. HAMILTON.
